UNITED STATES PATENT OFFICE.

HENRY C. HOLLINGER, SR., OF SPOKANE, WASHINGTON.

FILLER-APPLIER FOR FLOOR-CRACKS.

1,282,579.

Specification of Letters Patent. Patented Oct. 22, 1918.

Application filed April 16, 1917. Serial No. 162,469.

To all whom it may concern:

Be it known that I, HENRY CLAY HOLLINGER, Sr., a citizen of the United States, residing at 104 E. Trent avenue, in the city of Spokane, county of Spokane, and State of Washington, have invented a new and useful Filler-Applier for Floor-Cracks, of which the following is a specification.

This invention relates to filler applicators for floor cracks, and has for one of its objects to enable the filling of cracks in floors with a hot, firm, elastic and non-shrinking liquid from the bottom of the cracks up, so that when the filler cools and hardens, a solid and sanitary floor will be provided which will be impervious to germs or filth.

Another object is to provide a device of the class described which will enable cracks to be filled quickly and easily.

20 A further object is to provide a device of the class described, wherein the flow of filler may be readily regulated.

25 A further object is to provide a device of the class described which has incorporated therewith a safe and efficient means for heating, and maintaining at a heat, the liquid to be used in the applier.

30 A still further object is to provide a device of the class described which is simple in construction and cheap of manufacture.

Still further objects will be more clearly pointed out in the accompanying drawings and appended specifications and claims.

In the drawings:

35 Figure 1 is a side elevation of my device. Fig. 2 is a plan view with a portion of the handle broken away.

Fig. 3 is a plan view of the applier showing the cover and valve connecting rod re-
40 moved.

Fig. 4 is an enlarged view looking in the direction of arrow 4 of Fig. 4.

Fig. 5 is an enlarged section on line 5—5 of Fig. 2.

45 Fig. 6 is an enlarged section on line 6—6 of Fig. 7.

Fig. 7 is an enlarged section on line 7—7 of Fig. 2.

Fig. 8 is a section on line 8—8 of Fig. 1.

50 Fig. 9 is a fragmentary plan view of Fig. 8.

Fig. 10 is a section on line 10—10 of Fig. 7.

Fig. 11 is a section on line 11—11 of
55 Fig. 3.

Fig. 12 is an enlarged view looking in the direction of arrow 12 of Fig. 3.

At 10 I have indicated a liquid-filler reservoir provided respectively with a bottom 11, oval casing 12, squared end 13 and cover 14. 60 The cover 14 is removable, but is normally retained in position by means of the spring clasps 15 secured to cover 14 and apertured as at 16 to slip over lugs 17 provided on casing 12. In order to remove the cover 14 65 the clips 15 may be sprung out of engagement with lugs 17. In the cover 14 is provided the removable lid 18 which may be raised by means of rings 19. A handle secured to cover 14 is indicated at 20. An outlet nozzle is shown at 21, and I will now describe a means for normally closing outlet 21, together with means for manually opening the closure means. 70

Referring to Figs. 7 and 12, 22 indicates a plate which is secured to the squared end 13 by means of U bolts 23 and nuts 24. A pintle 25 is secured to plate 22 by means of the over-turned strips 26. A flap valve closure 27 is hinged to pintle 25 by means of 75 bearings 28 which consist of strips integral with closure 27, but bent over to form bearings. Felt or other suitable material 29 is secured to closure 27 by means of flanges 30 cut in the edge of closure 27 and turned over 80 as shown in Fig. 7. A lever 31 is integral with closure 27 and extends at substantially right angles thereto. A spring 32 is coiled about pintle 25, and one end 33 thereof bears against plate 22, and the other end 34 bears 85 against lever 31. It will thus be seen that the tension of spring 32 tends to hold felt 29 tightly against the outlet provided by nozzle 21. A lever 35 is loosely pivoted on a shaft 36 which bears in journals 37 provided on handle 20. Handle 20 is slotted as at 37' to allow for the swinging of lever 35, and also for the passage of rod 38 which connects the end 39 of lever 35 and lever 31. 90

Lever 35 is provided with a thumb-depression extension 40. By pressing downwardly upon extension 40 it will be seen that rod 38 will be raised, hence swinging lever 31 and closure 27 radially on pintle 25, thus allowing outlet nozzle 21 to communicate 95 with reservoir 10.

A locking member 41 extends upwardly from handle 20 and is notched as at 42. Lever 35 is provided with a laterally projected flange 43 which is adapted to engage 100

110

the notches 42. Due to the loose pivotal mounting of lever 35 on shaft 36, lever 35 may be swung to the left or right in Fig. 6 so that flange 43 may be withdrawn from 5 engagement with notches 42, so that in filling a crack of varying width a varying pressure may be maintained on thumb-extension 40 to allow a varying amount of 10 filler to enter nozzle 21. However, should it be desired to maintain a steady flow of 15 filler through nozzle 21, extension 40 will be depressed the required amount, and lever 35 swung to the left so that flange 43 will engage one of the notches 42, thus holding valve closure 27 away from nozzle 21 and 20 allowing the operator to release his thumb from extension 40 until such a time as he desires to change the flow of filler.

It will be understood that the filling substance will be inserted by raising lid 18 and dropping solid cakes of filler into reservoir 10. The cakes are melted by a means to be described later, but I will now point out my method for preventing any filler which may 25 remain unmelted from entering nozzle 21.

A baffle plate 44 is adapted to extend entirely across one of the reduced ends of casing 12, as shown in Figs. 3 and 10, and forms in conjunction with the casing a melting 30 chamber on the side of the plate remote from the outlet of the casing. Depending from plate 44 are legs 45 which will space the bottom 46 of plate 44 from the bottom 11. The legs 45 are bent as at 47 to slip into 35 sockets 48 which are secured to the bottom 11. Plate 44 may be removed by thrusting it to the left in Fig. 3, disengaging bent portions 47 from sockets 48. Wire screens 49 extend from the bottom 46 to the bottom 11. Should there be any chunks of 40 unmelted filler, it will be seen that plate 44 and screen 49 will prevent them from clogging nozzle 21, or impeding the operation of valve closure 27, it being understood that the 45 filler will not be introduced in sufficient quantity to over-run the top 50 of plate 44. The melter filler will flow through screens 49, which will also prevent foreign matter such as splinters and chunks of dirt from 50 entering nozzle 21.

My improved applying nozzle is best shown in Figs. 1, 4 and 5. The nozzle proper is shown at 51 and is provided with a V-shaped tip 52 which will more readily 55 direct the flow of filler into the crack 53 which is to be filled. A guiding flange 54 depends from nozzle 51 and is adapted to be inserted in the crack 53, so that as the nozzle 51 is drawn along the crack, flange 60 54 will hold the tip 52 in exact registry with crack 53 throughout its length. A connecting tube 55 extends between nozzle 21 and nozzle 51, being secured thereon by annular beads 56 and 57. When closure 27 is raised 65 to allow heated filler to pass through tube

55 and nozzle 51, it will be seen that nozzle 51 will become highly heated, and I therefore provide a hand-protection shield 58 for the purpose of protecting the hand of the operator. Shield 58 is preferably cone-shaped and is secured to nozzle 51 by webs 59 which will be of sufficient number to hold shield 58 rigid on nozzle 51, but not sufficient to carry a great amount of heat to shield 58. In order to aid in the radiation 70 of heat which may be carried to shield 58, I provide perforations 60 in shield 58.

Depending from the casing 12 are legs 61, to which is secured at 62 a heating unit generally indicated at 63. Skid portions 64 80 are provided on legs 61 so that the filler may be dragged along the floor. The heating unit consists of a fuel reservoir 65 consisting of sides 66, bottom 67 and top 68. Fuel such as alcohol may be 85 poured into reservoir 65 by removing cap 69 from filling tube 70. A flange 71 extends upwardly around the entire casing 66, and a wick-supporting cover 72 is adapted to fit thereover. It will be seen that the 90 air-cooling compartment 73 is thus formed. A plurality of circular screens 74 are inserted in apertures 75, and flanged sleeves 76 are adapted to slip through holes 75 in screens 74, and down through the cover 68. 95 Suitable wicks 77 are inserted in sleeve 76 and extend down into the fuel reservoir 65. Aperture 78 provides for the admission of fresh air to compartment 73. Wicks 77 will, of course, be lighted at their upper extremity 79 and it will be seen that all flame will 100 be separated from reservoir 65 by the compartment 73, thus preventing undue heating of the fuel in reservoir 65. The air in compartment 73 will find exit through screens 105 74 which will provide a draft for the flame caused by lighting wicks 79.

In operation, cakes of solid crack filler will be dropped into reservoir 10, and wicks 79 will be lighted. The heat from the 110 lighted wicks 79 will beat against the bottom 11 and cause the filler to be melted. The filler will find its way to the right of baffle plate 44, and upon depressing extension 40 will pass outwardly through nozzle 115 21, tube 55 and tip 52 into crack 53. The operator, after depressing extension 40, will simply walk backward dragging the entire filler applier along the floor on skids 64, maintaining guide flange 54 in crack 53 so 120 that the melted filler will pour into crack 53.

It will be seen that the melted filler will fill the cracks from the bottom up, leaving no unseen hollows to house germs or refuse. After the crack 53 is filled, any superfluous 125 filler which may have hardened above the surface of the floor, will be scraped off and re-melted in reservoir 10.

While I have herein shown and described one specific form of my invention, I do not 130

wish to be limited thereto, except for such limitations as the claims may import.

I claim:

1. In a device of the character described, 5 a filler reservoir having an outlet, means for controlling said outlet, a baffle plate within the reservoir forming in conjunction with the reservoir a melting chamber on the side of said plate remote from the outlet, said 10 baffle plate having a perforated lower portion to permit free flow of fully melted material to the outlet, and a heating device beneath the melting chamber.
2. In a device of the character described, 15 a filler reservoir having an outlet, means for controlling said outlet, a baffle device within the reservoir for preventing the flow of partially melted material to the outlet, a heating device beneath the reservoir, and a common support for the reservoir and heating device whereby they may be moved as a 20 unitary structure.
3. In a device of the character described, 25 a filler reservoir having an outlet, means for controlling said outlet, a baffle plate within the reservoir forming in conjunction with the reservoir a melting chamber on

the side of said plate remote from the outlet, legs depending from the baffle plate for spacing the bottom edge thereof from the 30 bottom of the reservoir, a screen extending from said plate to the bottom of the reservoir, and a heating device beneath the melting chamber.

4. In a device of the character described, 35 a filler reservoir having an outlet, means for controlling said outlet, sockets arranged on the bottom of the reservoir, a baffle plate within the reservoir forming in conjunction with the reservoir a melting chamber on the 40 side of the plate remote from the outlet, legs depending from said plate for spacing the bottom edge thereof from the bottom of the reservoir, laterally extending portions of said legs received in said sockets, a screen 45 extending from said plate to the bottom of the reservoir, and a heating device beneath the melting chamber.

In testimony whereof, I hereby affix my signature in the presence of a witness.

HENRY C. HOLLINGER, SR.

Witness:

H. E. SCANTLEBURY.
